US00D654790S

(12) **United States Design Patent**
Perell et al.

(10) **Patent No.:** US D654,790 S
(45) **Date of Patent:** ** Feb. 28, 2012

(54) **HOLDING CONTAINER WITH BREACHABLE PERIMETER BUBBLE**

3,608,709 A 9/1971 Pike
3,635,376 A 1/1972 Hellstrom
3,921,805 A 11/1975 Compere

(75) Inventors: **William S. Perell**, San Francisco, CA (US); **Leif B. Sorensen**, Cape Canaveral, FL (US)

(Continued)

(73) Assignee: **PopPack, LLC**, San Francisco, CA (US)

FOREIGN PATENT DOCUMENTS

DE 20314741 1/2004
(Continued)

(**) Term: **14 Years**

(21) Appl. No.: **29/384,247**

(22) Filed: **Jan. 28, 2011**

OTHER PUBLICATIONS

U.S. Appl. No. 12/434,254, filed May 1, 2009, Package with one or More Access Points for Breaking one or more Seals and Accessing the Contents of the Package.

(Continued)

Related U.S. Application Data

(63) Continuation of application No. 12/810,316, filed as application No. PCT/US2008/088100 on Dec. 23, 2008.

Primary Examiner — Susan Bennet Hattan

(74) *Attorney, Agent, or Firm* — Dority & Manning, P.A.

(51) **LOC (9) Cl.** 09-07

CLAIM

(52) **U.S. Cl.** D9/434

The ornamental design for a holding container with breachable perimeter bubble, as shown and described.

(58) **Field of Classification Search** D9/761, D9/737, 732, 707-710, 456, 453, 452, 435, D9/434, 425, 424, 416, 414; D3/304, 264; 222/94, 107; 206/522, 219, 205

DESCRIPTION

See application file for complete search history.

FIG. 1 is a perspective view of the holding container with breathable perimeter bubble showing the design;

FIG. 2 is a top view of the holding container with breathable perimeter bubble of FIG. 1;

FIG. 3 is a bottom view of the holding container with breathable perimeter bubble of FIG. 1;

FIG. 4 is a rear view of the holding container with breathable perimeter bubble of FIG. 1;

FIG. 5 is a front view of the holding container with breathable perimeter bubble of FIG. 1;

FIG. 6 is a left side view of the holding container with breathable perimeter bubble of FIG. 1; and,

FIG. 7 is a right side view of the holding container with breathable perimeter bubble of FIG. 1.
